UNITED STATES PATENT OFFICE

CHARLES DAVID BONSALL, OF PITTSBURGH, PENNSYLVANIA, ASSIGNEE TO P. H. MURPHY COMPANY, OF NEW KENSINGTON, PENNSYLVANIA, A CORPORATION OF PENNSYLVANIA.

CAR ROOF.

Application filed July 3, 1924. Serial No. 722,918.

To all whom it may concern:

Be it known that I, CHARLES DAVID BONSALL, a citizen of the United States, and a resident of the city of Pittsburgh, in the county of Allegheny and State of Pennsylvania, have invented a certain new and useful Improvement in Car Roofs, of which the following is a specification.

This invention relates to flexible car roofs, wherein metal roof sheets extend from eaves to eaves of the car and are loosely secured to the car and to each other by seam caps and permit relative movement of the sheets to a limited extent so as to be able to accommodate themselves to distortions of the car body.

The principal object of the present invention is to provide a simple and efficient arrangement that will secure an oscillatory movement of the sheets around a region near the middle or ridge portions of their side margins whenever there is movement of the sheets. Another object is to prevent damage to the sheets and caps during such movement. Another object is to simplify the operation of pressing the sheets and thereby reduce the cost thereof.

The invention consists principally in a car roof comprising roof sheets that extend from eaves to eaves and taper in width from ridge to eaves and are held down on the car and in approximate contact with each other at the ridge by means of seam caps that taper in width from eaves to ridge, whereby said sheets are forced to rock on each other or on the contacting portions of the seam caps whenever there is movement of the sheets. The invention also consists in utilizing the securing bolt for the running board saddle and the seam caps as a means for loosely holding the sheets in position at the ridge. The invention further consists in the parts and in the arrangements and combinations of parts hereinafter described and claimed.

In the accompanying drawing, which forms part of this specification and wherein like symbols refer to like parts whenever they occur,

Fig. 1 is a plan view of a portion of a car roof embodying my invention, parts being shown broken away to more clearly illustrate the invention;

Fig. 2 is an enlarged transverse section through one-half of the roof, the section

being taken between seams on the line 2-2 in Fig. 1;

Fig. 3 is a detail plan view of the ridge portion of the roof in the region of a seam;

Fig. 4 is a vertical cross-section through the seam at the ridge on the line 4-4 in Fig. 3;

Fig. 5 is a detail plan view of the roof in the region of one of the securing bolts for the eaves portions of the seam caps; and

Fig. 6 is a vertical cross section through a seam, the section being taken through said securing bolt on the line 6-6 in Fig. 5.

The present roof comprises metallic roof sheets 10 arranged transversely of the car and of sufficient length to extend from eaves to eaves thereof. As shown in the accompanying drawing, the roof sheets 10 are supported on a roof substructure comprising a ridge pole 11, purlins 12 and side plates 13, all of which extend longitudinally of the car from end to end thereof. Carlines 14 extend from side plate to side plate and support the ridge pole 11 and purlins 12. Side sheathing boards 15 and fascia boards 16 are secured to the side plates with their upper surfaces flush with the upper surfaces of the side plates.

The roof sheets 10 extend from side to side of the car and have depending eaves flanges 17 that overhang the outer edges of the fascia boards 16 and are spaced therefrom to provide sufficient clearance between the eaves flanges and the fascia boards to permit angular movement of said eaves flanges when the sheets sue in accommodating themselves to the distortions of the substructure. The roof sheets are pressed from sheet blanks of uniform width and their side marginal portions are bent upwardly and thence outwardly and downwardly to form side marginal flanges 18 of substantially inverted channel-shaped section that are of uniform height from the ridge line of the sheet to points adjacent to the eaves where they are curved downwardly and merge into the plane of the eaves end thereof. The inverted channel-shaped side marginal flanges 18 of the roof sheets are widest at the ridge and gradually decrease in width to the eaves so as to give the sheets a slight taper from ridge to eaves. The purpose of this taper is to afford greater clearance between the sides of the sheets at the eaves than at the ridge. The sur-

metal resulting from the gradual decreased width of the side flanges of the sheets from ridge to eaves causes a corresponding increase in the depth of the depending outer walls of said side flanges from ridge to eaves. It is noted that the reverse taper of the top and outside walls of the side flanges permits the sheets to be pressed from rectangular sheet blanks without requiring the blanks to be trimmed to a special shape before pressing.

The roof sheets are held down on the car and in approximate contact with each other at the ridge by means of channel-shaped seam caps 19 that extend from eaves to eaves of the car and are provided with depending eaves flanges 20 that overhang the sheets and are spaced therefrom. The seam caps straddle the upstanding side marginal flanges 18 of adjacent sheets and are provided with lateral base flanges 21 that rest on the body portions of said sheets. The seam caps are substantially in contact with the sides of the side flanges of adjacent sheets at the ridge and are of gradually increased width towards the eaves to permit the eaves than at the ridge. The seam caps are of a depth equal to or slightly greater than the height of the upstanding sheet flanges and are provided with downwardly curved eaves end portions that merge into the base flanges of the seam caps where they are turned down to form the depending eaves flanges.

Running boards 22 extend longitudinally of the car at the ridge and are supported on running board saddles 23 that rest on the transverse seam caps 19. The running board saddles 23 and seam caps are fastened to the substructure at the ridge by means of vertical carriage bolts 24 that extend downwardly through bossed up holes in the seam caps, between the side flanges of adjacent sheets, and through the ridge sole 11. At the ridge, the depending outer flanges of adjacent sheet flanges are recessed inwardly to form arcuate recesses in sockets 25 adapted to loosely embrace ridge bolts 24. The notches cooperate with the saddle bolts to loosely retain the ects in position at the ridge, but are of a shape that will permit the ridge slide on the adjacent side flanges to rock on of the seam caps during the sluing of the transverse seam caps are secured to the substructure by means of machine id that extend upwardly through holes in the outermost purlins and are threaded into cylindrical pieces rigidly secured to the tops of the seam

caps. The portions of the side marginal flanges of the roof sheets adjacent to cylindrical pieces or members that depend from the tops of the transverse seam caps are cut away or notched, as at 28, to permit the movement of the sheets relative thereto. By the arrangement described, the seam caps are positively secured to the roof structure at the ridge and adjacent to the eaves and thus serve to hold the sheets down on the car and in contact with each other at the ridge. This arrangement forces the sheets to roll or rock on each other or on contacting portions at the ridge seam caps whenever there is movement of the sheets. The narrow ridge portions of the seam caps serve to limit their contact with the sheets to the middle or ridge portions of their side seam flanges while the wide eaves end portions of said caps, together with the narrow eaves end portions of the roof sheets, provide sufficient clearance between the cooperating side flanges of the sheets and the side walls of the seam caps to permit angular movement of said flanges during the sluing of the sheets in accommodating themselves to the distortions of the sub-structure which occur in service.

The invention is not limited to the precise shapes and arrangements of parts shown and described. For instance, the sheets may be given the necessary taper from ridge to eaves by forming the sheets with reversely curved side margins.

What I claim is:

1. A flexible car roof comprising roof sheets arranged on the car side by side and extending from eaves to eaves thereof, said sheets having upstanding ribs along their opposite side margins, the side marginal ribs of adjacent sheets being spaced further apart at the eaves of the car than at the ridge thereof, and side seam caps straddling the adjacent side marginal ribs of said sheets whereby said sheets are adapted for independent oscillatory movement around a region near the ridge portion of either of their side margins.

2. A flexible car roof comprising roof sheets arranged on the car side by side and extending from eaves to eaves thereof, said roof sheets having upstanding ribs along their opposite side margins, the side marginal ribs of adjacent sheets being spaced further apart at the eaves of the car than at the ridge thereof, and side seam caps secured to the car and straddling the adjacent side marginal ribs of said sheets, said seam caps being of greater width at the eaves than at the ridge whereby said sheets are adapted for independent oscillatory movement around a region near the ridge portion of either of their side margins.

3. A flexible car roof comprising roof sheets arranged on the car side by side and

extending from eaves to eaves thereof, said roof sheets having upstanding ribs along their opposite side margins, the side marginal ribs of adjacent sheets being spaced 5 further apart at the eaves of the car than at the ridge thereof, and side seam caps secured to the car and straddling the adjacent side marginal ribs of said sheets, said seam caps having approximate contact 10 with the sides of the side marginal ribs of adjacent sheets substantially at the ridge and being normally spaced therefrom at the eaves whereby said sheets are adapted for independent oscillatory movement around 15 a region near the ridge portion of either of their side margins.

4. A flexible car roof comprising roof sheets arranged on the car side by side and extending from eaves to eaves thereof, said 20 sheets having upstanding ribs along their opposite side margins, said sheets being normally adapted for approximate contact with each other near the ridge portions of their side margins only, and side seam caps straddling the adjacent marginal ribs of said sheets and normally adapted for approximate contact with the sides of said adjacent side marginal ribs at their ridge portions only whereby said sheets are adapted for 25 independent oscillatory movement around a region near the ridge portion of either of their side margins.

5. A flexible car roof comprising roof sheets arranged on the car side by side and extending from eaves to eaves thereof, said sheets having upstanding ribs along their adjacent side margins that contact with each other at their middle portions only, and side seam caps secured to the car and straddling 30 the adjacent marginal ribs of said sheets, said side seam caps being normally in contact with the sides of said adjacent side marginal ribs at the ridge only whereby said sheets are adapted for independent 35 oscillatory movement around a region near the ridge portion of either of their side margins.

6. A car roof comprising a plurality of roof sheets extending from eaves to eaves 40 of the car, said sheets having upstanding ribs along their adjacent side margins that contact with each other at the ridge only, and seam caps secured to the car and spanning the adjacent side marginal flanges of 45 said sheets, said seam caps contacting with the sides of the adjacent flanges of said sheets at the ridge only whereby said sheets are adapted for independent oscillatory movement around a region near the ridge 50 portion of either of their side margins.

7. A car roof comprising a plurality of roof sheets that extend from eaves to eaves of the car and have upstanding flanges along their side margins, said sheets tapering in

width from ridge to eaves, whereby the side 65 marginal flanges of adjacent sheets are spaced further apart at the eaves than at the ridge, and seam caps secured to the car and spanning the side marginal flanges of adjacent sheets, said seam caps tapering in 70 width from eaves to ridge where they contact with the side marginal flanges of adjacent sheets and hold them substantially in contact with each other whereby said sheets are adapted for independent oscillatory movement around a region near the ridge portion of either of their side margins. 75

8. A car roof comprising a plurality of roof sheets that extend from eaves to eaves and have upstanding flanges along their side 80 margins, and seam caps secured to the car and straddling the side marginal flanges of adjacent sheets, the side marginal flanges of adjacent sheets being in contact with each other only in the region of the ridge and the seam caps being in contact with the sides of said adjacent flanges only in the region of the ridge whereby said sheets are adapted for independent oscillatory movement around a region near the ridge portion of 85 either of their side margins.

9. A car roof comprising a plurality of roof sheets that extend from eaves to eaves of the car and are formed with side marginal flanges of substantially inverted channel-shaped section, and seam caps secured to the car and straddling the seam flanges of adjacent sheets, the side marginal flanges of said sheets being wider at the ridge than at the eaves and said seam caps being wider 100 at the eaves than at the ridge whereby said sheets are adapted for independent oscillatory movement around a region near the ridge portion of either of their side margins. 105

10. A flexible car roof comprising a plurality of roof sheets arranged on the car side by side, side seam covers secured to the car and spanning the side margins of adjacent sheets, and means for securing an independent oscillatory movement of each roof sheet around a region near the middle of either of its side margins whenever there is movement of the sheet. 110

11. A flexible car roof comprising a plurality of roof sheets arranged on the car side by side and extending from eaves to eaves thereof, side seam covers secured to the car and spanning the side margins of adjacent sheets, and means for securing an independent oscillatory movement of each roof sheet around a region near the ridge portion of either of its side margins whenever there is movement of the sheet. 115

Signed at Chicago, Illinois, this 23rd day 120 of June, 1924.

CHARLES DAVID BONSALL.
